PROTECTOR FOR ELECTRIC CIRCUITS

George N. Lemmon, Homewood, Ala.

Application October 1, 1934, Serial No. 746,384

9 Claims. (Cl. 200—126)

The purpose of this invention is to prevent single-phase operation of a three-phase circuit which is protected by fuses.

On such a three-phase circuit, when one line is opened by the blowing of a fuse, the two other lines still carry single-phase current to such motors as are then in operation. This is undesirable, and my device causes the blowing of the fuses in both of the other lines in case any one of the three lines becomes open-circuited by the blowing of a fuse.

This invention can be used when there is but one fuse for each line but it is particularly useful when used in conjunction with repeater fuses, such as are shown in my Patent No. 1,954,634 issued April 10, 1934. On such a repeater fuse, the No. 1 tube with its fuse-link is normally in circuit while the No. 2 and No. 3 tubes are in reserve position. When the No. 1 fuse blows, its tube drops open and then the No. 2 fuse closes up into circuit-closing position. Similarly, blowing the No. 2 fuse brings No. 3 into circuit. If the No. 3 fuse also blows the circuit remains open until re-fused. A three-phase circuit protected by reeated fuses becomes single-phased only after the third fuse has blown in one of the three lines. Therefore my protector device is preferably arranged so that it operates upon the blowing of the No. 3 fuse in any one of the lines.

High voltage circuits cannot be opened successfully in free air; but when a fuse blows inside of an expulsion tube the explosive effect stops the flow of current. When one of the No. 3 fuses has ruptured, my protector device places a short-circuit across all three lines of the circuit. This causes all the other fuses to blow and so leaves the circuit fully opened instead of leaving it single-phased. The short-circuiting arms of the device are preferably connected solidly together and all grounded; but if desired one or more resistance elements, properly insulated, can easily be included to limit the overload imposed when the device operates.

Referring to the drawings, Fig. 1 shows part of a three-phase circuit with three repeater fuses installed, together with my protector. Fig. 2 is a side view of the same from the right side; Fig. 3 is a partial section, in larger scale, of the operating mechanism of the protector; and Fig. 4 is a similar front view of the mechanism, while Fig. 5 shows the grounding bar in operating position.

In Fig. 1 three incoming lines are indicated by 1, 2 and 3, while lines to the load are indicated at 4, 5 and 6. Dotted lines are used to

avoid interference with parts of the protector itself. The three fuses normally in service are 7, 8 and 9. The fuse link 9' is in service, the fuse link 16'' is in reserve position, and 15' shows a portion of the blown fuse link. Near the fuses is the grounding shaft 10, to which are attached three ground-arms, 11, 11, 11.

The trip-shaft 12 is near the ground-shaft, and both shafts are supported by the housings 13, 13, 13. Near one end of the trip shaft is the control-arm 14. Each housing also carries a tube 15 which has a projecting plunger 17, so placed that the plunger will be struck whenever one of the No. 3 fuse tubes, 16, 16, 16 blows its fuse-link and drops to the open position 16'. The ground-shaft 10 is partially rotatable and when so rotated moves all three ground-arms from the position 11 to 11'. Inside each housing 13 the shaft 12 has secured to it an arm 18 and adjacent to this arm is twist-arm 19, supported on a stud 20 and biased towards 18 by the spring 21.

The arm 19 has an end 22 which is held by the latch 23. A spring 24 biases the latch 23 against release, and the extension 25 of the latch arm 23 is in line with the inside end 17' of the plunger 17.

Inside the housing 13, the shaft 10 has secured to it an arm 26 which is biased by the spring 27 to move the ground-arms 11 up to the position 11'. Inside of one or more of the housings, the arms 18 and 26 are connected by the link 28. A suitable stop 29 allows the linkage 18—28 to come somewhat beyond the straight-line position. When in this position this linkage forms a positive toggle-lock to prevent rotation of 26 and 10. A latch 30 pivoted on the pin 31 is biased by the spring 32 so that it can engage with the stud 33 in the arm 18, thereby preventing backward rotation of the arm 18 and the shaft 12.

Supported by the end housing 13 is the control arm 14, which is movable to rotate the shaft 34 and the crank and pin 36 which are inside the housing. This pin 36 engages against the arm 18 so that it can rotate 18 clockwise when 14 is moved from 14 to 14' as shown in Fig. 2, and when 36 is thereby moved from the position shown in Fig. 3 by full lines to the position shown by dotted lines. When the outside arm is in the position 14, the pin 36 is away from 18 and the end 36' is engaged with 30 so that 30 is disengaged from the stud 33. In this position the device is ready to function.

Under such conditions 12 can be rotated, thereby releasing the toggle-lock of the linkage

18 and 28, whereupon the spring 27 rotates the arm 26 and the shaft 10, in clockwise motion.

Operation is as follows: If one of the No. 3 tubes on any of the repeater fuses drops to the 5 position 18, its strike 17 and drives 17' against 28. This releases 23 from 22, and 21 rotates 19 against 18, moving the toggle-joint 18 and 28 beyond the center position. Thereupon 27 rotates 28 to the position 26', and this rotates 10 10 and brings all the ground arms to the position 11', in connection with the conductors 4, 5, 6. Thereby the remaining fuses in the two other lines are all blown, and the three-phase circuit is completely open. A contact member 6' may be 15 used to avoid any burning of the line conductor 6.

When the line trouble has been cleared the equipment is re-fused as follows: With an insulated stick, the operator pulls down 14 to 14' as far as possible. This rotates 36 against 18, and 20 so rotates the whole shaft 12 until every member 18 has been pushed back, tensing 21 and engaging 22 with 23. The stop 29 is reached by 28 only after 22 and 23 are engaged. At the same time 30 has engaged with 33, locking the protector 25 open. The man then re-fuses the repeaters in the usual way placing the No. 1 tubes all in service and the No. 2 and No. 3 tubes all in reserve position. He then pushes the control arm from 14' up to 14, which lifts 30 away from 33 and engages 36' with the notch in 30. The spring 32 acts to hold 30 over 36', thereby keeping the arm 14 up until it is forcibly pulled down.

The equipment is thus again set ready to operate automatically.

35 I am not limited to the methods of construction here shown, for the details can easily be modified in many ways without departing from the fundamental principle of my invention. Also my invention can be easily applied to single fuses 40 or to repeater fuses having other than three tubes per phase.

I claim:

1. A protector for electric circuits comprising 45 a conductor, a plurality of fuse containers connected to the conductor, a fuse within each container, an adjacent fuse in series with an adjacent conductor, together with automatic means to blow the adjacent fuse, the operation of said last means being initiated by motion of one of 50 the said containers.

2. A protector for an electric circuit comprising automatic means to short-circuit all the conductors of the circuit, a fuse in circuit with each

of said conductors, a container for each fuse, together with means operable by the motion of one of the said containers to initiate the operation of the said automatic means.

3. A protector for an electric circuit comprising 5 automatic means to short-circuit all the conductors of the circuit, a plurality of fuses connected to each of said conductors, a container for each fuse, together with means operable by motion of one of said containers to initiate the 10 action of said automatic short-circuiting means.

4. In combination, a conductor, a plurality of fuses connected therewith, another fuse adjacent thereto, automatic means operable upon the rupture of a certain one of the first fuses to rupture 15 the said adjacent fuse.

5. Protection for electric circuits comprising a plurality of circuit conductors, a plurality of fuses associated with one of said conductors, a 20 fuse associated with another of said conductors together with automatic means to blow the last said fuse upon rupture of the last of said plurality of fuses.

6. Protection for electric circuits comprising a plurality of circuit conductors, a plurality of 25 fuses associated with each of said conductors, together with automatic means operable upon the rupture of all fuses associated with any one of the said conductors to rupture all of the fuses associated with one of the other said conductors. 30

7. Protection for electric circuits comprising a plurality of circuit conductors, a plurality of fuses connected to each of said conductors, together with automatic means operable upon the 35 rupture of all fuses connected to any one of the said conductors to rupture a fuse connected to each of the other said conductors.

8. Protection for electric circuits comprising a plurality of circuit conductors, a plurality of fuses associated with each of said conductors, 40 together with automatic means operable upon the rupture of all fuses associated with any one of the said conductors to rupture all of the other said fuses.

9. Protection for electric circuits comprising a plurality of adjacent conductors, circuit interrupting means in series with each conductor and operable independently of each other, together with automatic means operable after a pre-determined number of operations of one of said 45 circuit interrupting means to operate another of said circuit interrupting means.

GEORGE N. LEMMON.
